UNITED STATES PATENT OFFICE

2,592,013

GOLF CLUB

Thomas F. Curley, Atlantic City, N. J.

Application July 7, 1950, Serial No. 172,585

5 Claims. (Cl. 273—77)

1

My invention relates to new and useful improvements in golf clubs and more particularly to the wooden clubs, and has for an object to provide the head of the golf club with weights or projectiles so that there will be an additional impact or blow transmitted to the ball when the club face strikes the same.

The invention in its broadest aspect is somewhat similar to the structure shown in the patent granted to H. B. Febiger on January 14, 1902, bearing Patent No. 690,940.

In the patent above mentioned there are shown two weights mounted for movement in the head of the club, so that when the ball is struck, the weights will travel forwardly and thus add an additional impact when the ball is struck. However, in that instance, there was no means provided to assure the user that the weights were in a position to travel forwardly to add the impact when the club strikes the ball, and the probabilities are that as the golf club head is raised on the upward rear swing, the weights would slide to the face of the club rather than be in their rearward position; and then when the club is brought downwardly, the weights rather than being in their rearward-most position would not travel forwardly to add the impact desired, so that the only advantage, if any, would be the additional mass or weight of the club.

Furthermore, there was no provision made to prevent an air cushion, so that the force of the impact in all probability would be lowered or cushioned.

One of the objects of the present invention is to provide weights or what might be termed projectiles in the head of the club and to provide a tube or barrel for these weights, so that they may travel freely; and, most important, to provide a magnet behind each weight so that the weights will normally be in their position to travel and be forced against the inner face plate of the club when the golf ball is struck by the club.

Still another object of the invention is to provide one or more weights that are to be mounted for movement in the relatively short barrels or tubes; and in some instances, one or more of these tubes may be inserted in a small casing as a unit, so that to apply these weights to the head, it is only necessary to cut out a portion of the club and readily insert the relatively small unit.

Still another object of the invention is to provide a golf club with one or more weights therein that travel from a point near the rear of the

2

club to the face plate, and these weights in turn are each mounted in a non-ferrous tube and normally held in position by a small magnet mounted at the rear of the tube.

Thus, after the ball is struck and the golf club put back in the golf bag, the possibilities are that the weights will have moved backwardly within the field of magnetism and snapped back in position; or, the golfer can, when he takes the club out of the bag, move the club and, not hearing a movement of the weights, he is assured that they are in their position to move forwardly. If, on the other hand, he hears a slight movement of the weights or feels a slight movement when moving the club, he can turn the club slightly in his hand before using it to make sure that the weights are back in their proper position to be shot forwardly.

With these and other objects in view, the invention consists in certain new and novel arrangements and combinations of parts, as will be hereinafter more fully described and pointed out in the claims.

Referring now to the drawings, showing a preferred form and several modifications,

Fig. 1 is a view in elevation of the head of a wooden golf club and a portion of the shaft, and the dotted lines about centrally of the face showing one of the weights mounted therein.

Fig. 2 is a vertical cross-section taken on line 2—2 of Fig. 1, looking in the direction of the arrows.

Fig. 3 is a perspective view on an enlarged scale of what I term a single unit, the parts being broken away to show the tube, the magnet and the sliding weight.

Fig. 4 is a cross-section taken approximately on line 4—4 of Fig. 3.

Fig. 5 is a vertical cross-section, similar to Fig. 2, on an enlarged scale, of a slightly modified form, showing two tubes, two magnets and sliding weights in a casing, and the casing arranged vertically within the head,

Fig. 6 is a similar horizontal sectional view of the golf club head showing the tubes, magnets and weights arranged horizontally with respect to one another,

Fig. 7 is a cross-section, similar to Figs. 2 and 5, of a further modified form, wherein the outer casing is omitted; and means provided to prevent any air cushion within the tube,

Fig. 8 is a horizontal sectional view, similar to Fig. 6, showing two tubes, magnets, and the weights, arranged horizontally with respect to one another, omitting the outer casing, and show-

ing means for the escape of any air within the tubes, and

Fig. 9 is an exploded view, showing one tube, magnet, and sliding weight for insertion in the club head, the tube and the weight both being perforate.

Referring more particularly now to the several views, and Fig. 1 for the moment, there is shown a wooden golf club, having the head 1, the shank 2, and a portion of the shaft 3. There may also be seen the face plate 4 held in position by the screws 5 and the under or heel plate 6 held in position by the screws 7.

Referring now for the moment to Figs. 2, 3 and 4, there is shown a rectangular casing 8 which is preferably made of a non-ferrous metal, such as aluminum; and in the same is mounted a tube 9 which at its rear end (Figs. 2 and 3) abuts against a permanent magnet 10, which is button-like in shape and preferably slotted across its front face as at 11 to form north and south poles.

In the tube 9 is a ferrous metal weight or projectile 12, which may be of iron or steel, so that it will be held when in the magnetic field of the aforementioned magnet 10.

It will be understood that the casing 8 that holds this tube 9, magnet 10 and projectile 12 is not hermetically sealed; and there is a slight air space between the forward end of the tube 9 and the face of the casing 8, so that the air within the tube 9 and in front of the projectile 12 may escape when the projectile 12 is moved forwardly.

However, in the modified form, to doubly assure that there will be no air cushion, I show apertures in the tube 9, as will be mentioned shortly.

It will be understood that the length of the projectile or weight 12 may vary, and the length of the tube 9 may also vary.

All that is necessary to do to insert what might be termed the unit 13 in the golf club head 1 is to remove the under or heel plate 6 and hollow out a chamber to hold the unit 13. The face plate 4 will also be cut out slightly on its inner face as at 14, so that the forward end 15 of the casing 8 will contact throughout its face with the cutout face 14 of the face plate 4, so that the weight or projectile 12 will impart its force when shot forwardly completely across its face against the wall 15 of the unit 13 and also against the flush inner face where it is cut out of the face plate 4. This cutout portion 14 of the face plate 4 may be seen on a little larger scale in Fig. 7 at 35, but in this instance there is no rectangular casing 8 used, as will shortly be mentioned.

The internal diameter of the tube 9 is slightly greater than the external diameter of the weight or projectile 12 to also prevent any air pocket or cushion within the tube 9, thus permitting the air to escape between the tube 9 and the outer surface of the cylindrical projectile or weight 12.

Now, when the club is handled, if the head 1 is tipped slightly, the projectile 12 will slide rearwardly; and as soon as the projectile 12 comes within the magnetic field of the magnet 10, it will be drawn thereto and normally held against the magnet 10. Then, when the club is raised on the back stroke, there is no possibility of the weight 12 pulling away from the magnet 10, as the magnet 10 is strong enough to prevent the projectile 12 from leaving the magnetic field by the force of gravity.

Then, when the club is used to strike the ball, to the impact of the club is added the additional

impact of the moving projectile, and with the same power exerted, the ball is caused to travel a greater distance than in the ordinary golf club.

It is thought that the duration of time that a golf ball is flattened by the impact of the swinging club until the time it leaves the club and regains its form is about eight ten-thousandths of a second; and it is during this time that this additional impact of the projectile 12 breaking away from the magnet 10 is imparted to the force of the club.

It will be understood that the magnet 10 is not so strong that it creates too great a drag but just strong enough to hold the projectile 12 against the magnet 10 until the ball is struck; and it is also thought that this sudden breaking away from the magnet 10 will add greater acceleration to the weight or projectile 12 and give a greater force of impact than if the magnet 10 were not used.

Referring now to the modification shown in Fig. 5, there is shown a portion of the golf club head 16 with the unit 17 therein, which unit 17 is similar to the unit 13, the difference being that here the unit 17 is substantially twice as large as the unit 13, as there are two tubes 19 and 20 and two projectiles 21 and 22 and two magnets 23 and 24. In this arrangement I mount the unit 17 in a vertical position with respect to the golf club head 16. The face plate 25 is cut out on its inner face as at 26 so that the inner face of the face plate 25 and the outer end of the casing lie flush.

In the form shown in Fig. 6, the unit 17 is placed in a horizontal position rather than in a vertical position, the remainder of the structure and elements being exactly the same as shown in the former figure, Fig. 5. In other words, in the one form the projectiles or weights 21 and 22 travel one above the other, whereas in Fig. 6 they travel side by side.

I can use either one unit as shown in the preferred form, or two; and this may depend on the size of the player, who may want a heavier club than where just a single unit is used.

Referring now to the slightly modified form, as shown in Figs. 7, 8 and 9, and referring for the moment to Fig. 7, there is shown a portion of the head 27, and, rather than mounting the several elements in a casing, I simply drill out the face of the head of the club as at 28 to place the button-magnet 29 near the rear face and then insert the tube 30, in which will travel the projectile or weight 31.

It will be seen in this form that I drill out the tube 30 transversely at its opposite ends as at 32 and I cut two small grooves in the club as at 33 and 34, which grooves register with the respective holes 32. The face plate 27' is then cut out as at 35 so that the projectile 31 will hit the inner surface of the face plate 27' squarely, and then the plate 27' is again replaced.

In Fig. 8 there is a still further modification, wherein the club head 27 has the parts just mentioned duplicated as at 36 and 37.

In Fig. 9, an exploded view, I have shown the magnet 10 with its slot 11 therein to form the north and south poles, the projectile 12, and the non-ferrous tube 9, and this tube may have the holes 32 therein to prevent any air cushioning of the forward-moving projectile 12; and the weight 12 may have a central bore 32' to also prevent any air cushioning.

The magnets assure that the projectiles will be in their proper position to be shot forward on the impact with a ball when the ball is struck, to therefore impart an additional force upon the

contact and follow-through, and thus cause the ball to travel a greater distance.

I am of the opinion that the magnet, by holding this projectile within its field and then allowing it to break away from the field, may create a greater force than if the projectile were not held by a magnet.

It is also within the province of my invention to hermetically seal the casing 8 and evacuate the air so that the weight 12 will travel in a vacuum.

I am also of the opinion that by having these projectiles shoot forward on the impact of the blow, it will cause the club to strike the ball squarely and thus lessen the tendency to put a twist on the ball, which causes a slice or hook.

The club in practice has definitely proved that a player using the same ball and the present club may drive the ball farther than with the ordinary form of club.

I am aware that it is old to place additional sliding weights in a golf club head and I do not broadly claim my invention as such, but what I do claim and desire to secure by Letters Patent is:

1. A golf club head having a percussion unit mounted in said head, said unit including a non-ferrous metal casing, a non-ferrous metal tube, a magnet mounted to the rear of the tube, a ferrous metal projectile slideable in said tube all enclosed within said casing, and the projectile adapted to break from said magnet and add additional impact to a golf ball when the said ball is struck by said club.

2. A golf club head having a face plate thereon, a percussion unit mounted in said head and abutting the inner face of said face plate, said unit including a non-ferrous metal casing, a non-ferrous metal tube, a magnet mounted to the rear of the tube, a ferrous metal projectile slideable in said tube all mounted within said casing, and

40

the projectile adapted to break from said magnet to strike said face plate and thus add additional impact to a golf ball when struck by said club.

3. A golf club head having a ferrous metal weight therein, movable from near the rear of the golf club head to the inner surface of the striking face of said head, magnetic means for normally holding the weight in its rearward-most position, and means for preventing an air cushion in front of the ferrous metal weight.

4. A golf club head having a non-magnetic tube mounted therein, a ferrous metal weight slideably movable in said tube, magnetic means for holding the weight in its rearward-most position in the tube, and said tube provided with perforations to prevent an air cushion in the tube when said weight moves forwardly.

5. A golf club head having a non-magnetic tube mounted therein, a ferrous metal weight provided with a central bore, said weight slideably movable in said tube, magnetic means for holding the weight in its rearward-most position in the tube, and the bore in said weight adapted to prevent an air cushion in said tube when said weight moves forwardly.
